WOOD-BENDING APPARATUS

Clarence A. Jordan, Madison, Wis.

Application October 25, 1946, Serial No. 705,786

5 Claims. (Cl. 144—264)

(Granted under the act of March 3, 1883, as
amended April 30, 1928; 370 O. G. 757)

1

This application is made under the act of March 3, 1883, as amended by the act of April 30, 1928, and the invention herein described, if patented, may be manufactured and used by or for the Government of the United States of America for governmental purposes without the payment to me of any royalty thereon.

I hereby dedicate the invention herein described to the free use of the People in the territory of the United States to take effect on the granting of a patent to me.

This invention relates to an improvement in apparatus for bending wood, for example, wood that has been given a softening treatment with steam, hot water, or chemicals. The improvement is in a modified tension strap and reversed levers for applying end pressure and has the following objects:

To provide rigid end blocks which cannot tip or back away from the ends of the stick being bent;

To provide convenient adjustment to accommodate different lengths of bending sticks;

To control end pressure;

To provide a convenient arrangement for using a minor strap to hold the bent member to shape after removal from the apparatus;

To provide reversed levers and strap which are separate pieces, so that by having a number of straps of different lengths it is possible to bend any length stick, using the same pair of reversed levers for all.

I attain these objects by the device illustrated in the accompanying drawings, in which

Figure 1 is a three dimensional view of the wood-bending apparatus showing the stick being bent around a wooden form;

Figure 2 is a face view of the metal strap with integral adjusting screws at each end;

Figure 3 is a view of the reversed lever having an integral end-block bracket and a removable end block;

Figure 4 is a side view of the assembled strap, reversed levers, removable end blocks and minor strap in place;

Figure 5 is a view in section taken at line 5—5 of Figure 4;

Figure 6 is a view in section taken at line 6—6 of Figure 4;

In Figure 2 is shown the metal strap 4 having an adjusting screw 2 fastened thereto, or integral therewith, at each end. The bending lever or reversed lever 1, shown in Figure 3, comprises a U-shaped bar 6 having walls 12 and 13 integrally or ridgedly attached to an end-block bracket.

2

The bracket consists of end and side walls 8 and 9 and top and bottom walls 7. Wall 8 is perforated at 14 to receive the adjusting screw 2, and at 15 for attachment of cable 19.

One mode of application of this invention is shown in Figure 1. A wooden stick 11 is bent around form 18 by pulling cables 19 attached at 15 to brackets 1. Between the metal strap 4 and the stick 11 is the minor strap 10. Before placing the movable blocks 5, the minor strap 10 is placed on metal strap 4 with the ends of the minor strap fitting against and projecting beyond the brackets. The ends of the minor strap may be provided with means such as holes 16, or the equivalent, to which a cable 17 may be attached after the wood-bending operation. The ends are thus fastened together when the bend is completed, thereby preventing the bend from springing back when removed from the bending apparatus.

In use, the adjusting screws 2 are passed through the holes 14 in the ends of the brackets, and are fitted with washers and with adjusting nuts 3. Removable end blocks 5, milled out to fit the end-block brackets, are brought to bear against the ends of the piece being bent, by tightening the adjusting nuts. End pressure is applied or released by manipulation of the adjusting nuts 3 prior to and during bending.

As stated above, this bent member must be held in the bent shape until the wood has cooled and become set in its new shape. For this purpose, the so-called minor strap of lighter metal than the tension strap is often placed between the tension strap and the stick before bending, the ends being fastened together when the bend is completed, thereby preventing the bend from springing back when removed from the bending apparatus.

This invention, with its removable end blocks 5, permits a minor strap to be laid flat against the tension or major strap with ends extending out between the major strap and the end blocks. When the bend is completed the ends of the minor strap can be merely bent around the end blocks and fastened together, leaving the end blocks in place against the ends of the bent stick. Additional pairs of end blocks are used for making further bends.

Having thus described my invention, I claim:

1. In a wood-bending apparatus, a tension strap, a bending lever for each end of the strap, the outer end portions of the levers being attached to the strap, the unattached inner ends of the levers extending longitudinally back of the ten-

sion strap, a bracket fixed upon and intermediate the ends of each lever and having a transverse end pressure applying face, and open-ended aperture in each transverse face, a removable end block over the inner face of each aperture between the aperture and the end face of the wood being bent, a minor strap between the wood being bent and the tension strap, the ends of the minor strap being free of the tension strap and of the levers and extending longitudinally outwardly through and beyond the apertured transverse faces, whereby, after the bending is done, and upon tying the ends of the minor strap, the minor strap, bent wood, and end blocks are removable from the tension strap as a unit, the end portions of the minor strap passing through the open ends of the apertures for the purpose of said removal.

2. In a wood-bending apparatus, a tension strap having a middle portion adapted to support the back of a piece of wood to be bent, a bending lever mounted upon each end of the strap, one end only of each lever being attached to an end of the strap, the unattached end extending longitudinally back of the strap, a bracket fixed upon each lever intermediate with the ends of the lever, the bracket having a transverse face adapted to be brought to bear pressure against an end face of the wood being bent, an open-ended aperture in said transverse face, a minor strap placed between the tension strap and the wood, the ends of the minor strap extending longitudinally through the apertures and beyond the transverse faces of the brackets, the minor strap being unattached to the tension strap and to the bending lever, the end portions of the minor strap being removable from the tension strap through the open-ended apertures, whereby after the bending is done, and upon tying the ends of the minor strap, the minor strap and bent wood are removable as a unit.

3. In a wood-bending apparatus, a tension strap having a middle portion adapted to support the back of the piece of wood to be bent, a bending lever positioned on an end portion of the tension strap and movable longitudinally thereon, a second bending lever on the other end portion of the tension strap, the bending levers each comprising a lever portion adapted to be brought to bear against the back of the piece of wood to be bent adjacent to an end face of the latter and an end bracket rigidly affixed to the lever portion which bracket has a surface that is angularly disposed to the lever portion and which surface is adapted to be brought to bring pressure to bear against said end face of the piece of wood to be bent, means for adjusting the movably positioned bending lever lengthwise of the tension strap whereby pressure may be applied to and released from the ends of the piece of wood to be bent, each of said bracket surfaces having an open-ended aperture, a minor strap between the tension strap and the back of the piece of wood, the minor strap having free ends extending longitudinally of the tension strap outwardly through and beyond the said open-ended apertures, the ends of the minor strap being removable through the open-ended apertures, whereby the piece of wood and the minor strap are removable as a unit upon completion of the bending operation.

4. In a wood-bending apparatus, a flexible tension strap having a middle portion adapted to support the back of the piece of wood to be bent, said tension strap having an adjusting screw at

each end thereof; and a rigid bending lever adjustably positioned on each adjusting screw, each bending lever having a rigid end bracket which has a transverse surface adapted to be brought to position to apply pressure against an end of the piece of wood to be bent, each of said bending levers having a lever portion comprising a bar adapted to be made to bear against the back of the piece of wood adjacent to said end of the latter, the bracket being rigidly fixed to the lever portion and having a second transverse surface having an aperture through which the adjusting screw extends, and an adjusting nut on each screw which is movable longitudinally thereon and thus brought to bear against said second transverse surface, whereby pressure may be applied to and released from the ends of the wood being bent prior to and during the bending operation by turning said adjusting nut, each of said first transverse surfaces having an open-ended slot aperture, the ends of the tension strap passing longitudinally through said open-ended apertures, and removable blocks in position between the first transverse surfaces and the ends of the piece of wood, said blocks each having an extension that fits in the slots.

5. In a wood-bending apparatus, a bending lever, adapted for use with a tension strap in bending an elongated stick of wood, comprising a composite bar, having a portion that extends under the tension strap and one end portion of the stick, this portion of the bar having a U-shaped cross section with the open part of the U facing away from the tension strap, and having another portion extending longitudinally beyond the end of the stick, which latter portion of the bar is also of U-shaped cross section but with the open part of the U facing toward the tension strap, the sides of the U-bar of one portion being extensions of the sides of the U-bar of the other portion and the bottom of the U-bar of the latter portion of the lever extending back under the piece of wood to be bent a short distance, giving that short sub-portion of the bar a rectangular-shaped cross section, the side walls of the portion of the bar that extends longitudinally beyond the end of the stick having two transverse flanges, one flange facing the end of the stick, the second flange being adjacent the end of the bar, the first flange having an open-ended slot aperture, a removable end block, at each end, between the first flange and the end of the stick of wood, the block having an extension that projects within the slot, the ends of the tension strap extending underneath the blocks and longitudinally through and beyond the slot apertures and being fastened at the ends to the second flanges, and means by which a bending force can be applied to the second flanges.
